UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

LOCK.

1,302,863.

Specification of Letters Patent.

Patented May 6, 1919.

Application filed January 31, 1918. Serial No. 214,765.

To all whom it may concern:

Be it known that I, JOHN H. SHAW, a citizen of the United States, residing in the city and county of New Haven, State of Connecticut, have invented certain new and useful Improvements in Locks, of which the following is a full, clear, and exact description.

This invention relates to locks, and more particularly to the type of mortise lock having inside and outside dead bolts, with operating means whereby the inside dead bolt may be retracted by protracting the outside dead bolt.

A number of the mortise locks now in general use, especially in hotels, are provided with what are known as inside and outside dead bolts, the arrangement being such that one of the bolts, known as the outside bolt, is operated by inserting the key in the key hole from the outside of the door, and the inside bolt is operated by a key inserted from the inside of the door. This type of lock is usually provided with additional means whereby it is possible to retract the inside bolt by protracting the outside bolt. This arrangement is often necessary, in order that it may be possible to unlock a door from the outside of the same in case the person inside the room has been taken ill, or for some other reason fails to unlock the inside bolt when it is necessary to enter the room.

The object of my invention is to provide the type of mortise lock just referred to with means which will make it very difficult to retract the inside bolt by protracting the outside bolt with any key except the one that is especially designed for this purpose.

More particularly, the object of my invention is to form what I have termed a floating ward upon the rear end of the inside bolt, so that when this bolt is protracted the floating ward is moved into the path of rotation of the bit of the outside key, so that none of the keys of the series provided for the lock, when inserted from the outside of the door, can be turned in the lock, except the key the bit of which is so constructed that it will clear the ward, which key is usually the one possessing the highest order of the whole series.

To these and other ends, the invention consists in the novel features and combina-

tions of parts to be hereinafter described and claimed.

In the accompanying drawings:

Figure 1 is an elevation of a lock embodying my improvements, the inside dead bolt being shown protracted, and a part of the cap plate being broken away in order to disclose more clearly my improved mechanism;

Fig. 2 is a view similar to Fig. 1, showing the inside dead bolt in its retracted position;

Fig. 3 is a rear edge view of the lock shown in Fig. 1, a portion of the mortise lock case being broken away in order that the coöperation between the floating ward and key may be clearly seen;

Fig. 4 is a side view of the inside dead bolt removed from its lock;

Fig. 5 is a rear end view of this bolt; and Figs. 6 and 7 are views of two of the keys with which my lock is provided.

Referring to the drawings, the case 10 of the lock is provided with an outside bolt 11 and an inside bolt 12. The former bolt is adapted to be operated under different conditions by any one of a series of keys, one of which is designated as 13, Fig. 6, and another as 13', Fig. 7. The other dead bolt 12 is adapted to be operated by the same keys or by another key 14. The bolt 11 is preferably provided with a number of locking tumblers and other coöperating parts with which locks of this type are usually provided, which parts have not been shown since they in no way relate to my particular improvement.

The inside dead bolt 12 is provided with the talons 15, by means of which the bolt may be operated by the key 14 inserted from the inside of the door. This bolt is also provided with a notch 16, which coöperates with a stump or post 17, by means of which the outward and inward movement of the bolt is limited. The bolt 12 is further provided with the tumbler 18, which is pivotally mounted on the projecting lug or pin 19 and coöperates with the stump 17. The lock is further provided with a lever 19', whereby, if the outside bolt is shot forward while the inside bolt is protracted, the outward movement of the outside bolt will retract the inside bolt. This connecting lever is not illustrated in detail, since its use and operation

is well-known and forms no part of this invention.

The object of my invention, as above mentioned, is to provide means whereby none of the keys of the series with which the type of lock herein described is usually provided can be rotated in the lock to protract the outside bolt while the inside bolt is in its protracted position, except the key which is so constructed that its bit will clear the ward. This key is usually the one possessing the highest order of the entire series of the keys with which the lock is provided. I accomplish this object by providing the inside bolt 12 with what I term a floating ward 20, formed upon the rear end thereof and projecting laterally therefrom, so that when the bolt upon which it is formed is protracted, the ward lies in the path or arc through which the bit of the outside key must be swung in order to bring the same into operating engagement with the talons of the bolt 11. The ward 20 preferably consists of a flange 20' positioned to have sliding engagement with one wall of the case 10 and of a second flange 20'' formed integral with the first flange and extending at right angles thereto. The flange 20' is provided with one or more slots 21, which are so formed that they will permit the bit of the key 13 to pass therethrough when the bolt 12 is protracted, but will prevent any other key of the entire series with which the lock may be provided from being rotated after the same has been inserted in the key hole from the outside of the door. It should be noted that the floating ward 20 is not merely a lug or similar projection which is adapted to contact with the lower end of the bit, in order to prevent a key, the lower edge of which does not clear the lug, from being rotated in the lock when the inside bolt is protracted, but that this ward lies in a plane at substantially right angles to the axis of the bolt 12 and extends substantially across the width of the case 10, the arrangement being such that, when the bolt 12 is protracted, no key inserted in the key hole from the outside of the door, no matter what shape it may possess, can be rotated in the lock unless the bit of the same is cut so that the projecting portions of the same will pass through the slots 21.

In Fig. 6 of the drawing, I have shown the key I have used to represent the highest order of the entire series with which the lock may be provided, which key is usually called the "emergency master key", and in Fig. 7, I have shown the key 13', possessing the next highest order of the series, and which is usually termed the "grand master key." It will be apparent, from an inspection of Figs. 6 and 7, that the emergency master key could be rotated, but that the grand master key, which is the next highest key in the order, could not be rotated in the lock to protract

the bolt 11 when the inside bolt 12 has been protracted, as the L-shaped portions formed upon the outer edge of the bit would prevent the same from passing through the slots 21 formed in the floating ward 20.

From the above description, it will be apparent that when a person has locked himself in a room possessing the type of lock herein described, no one will be able to unlock the door from the outside of the same, except the person possessing the key which is particularly designed for this purpose, and that the other keys of the series with which the lock may be provided will not pass the ward 20. This key, when a lock provided with the same is mounted upon the door of the guest chamber of a hotel, is kept in the possession of some thoroughly reliable person, such as the manager or desk clerk of the hotel.

What I claim is:

1. In combination, in a multiple key lock, a plurality of dead bolts, a floating ward formed upon the rear portion of one of said bolts, said ward having slotted clearance spaces formed therein to permit the bit of but one key of the series to pass the ward.

2. In combination, in a multiple key lock, inside and outside bolts, a ward formed upon the rear portion of said inside bolt, said ward formed to lie substantially in a plane transverse to the axis of the inside bolt and constructed to permit one key of the series of multiple keys to be rotated in the outside key hole but to prevent the other keys of the series from rotating therein when the bolt upon which the ward is formed is protracted.

3. In combination, in a multiple key lock, inside and outside dead bolts, a ward formed upon said inside bolt, said ward positioned to lie in the path of rotation of the outside key when the inside bolt is protracted and constructed to permit the bit of only one key of the series of multiple keys to pass said ward when the inside bolt is protracted.

4. In combination, in a multiple key lock, inside and outside dead bolts, a ward formed upon said inside bolt, said ward positioned to lie in the path of rotation of the outside key when the inside bolt is protracted, said ward having clearance slots formed therein and positioned to permit the bit of only one key of the series of multiple keys to pass said ward when the inside bolt is protracted.

5. In combination, in a multiple key lock, inside and outside bolts, a ward formed upon said inside bolt, said ward positioned to lie in the path of rotation of the outside key when the inside bolt is protracted and provided with a portion extending substantially in a plane transverse to the axis of the inside bolt, said portion being constructed to permit the bits of some of the keys of the series of multiple keys to pass

said ward but to prevent the remaining keys from passing when the inside bolt is protracted.

6. In combination, in a multiple key lock, 5 a lock case having a key hole, bolts in said case, a slotted ward formed upon one of said bolts, said ward positioned to be moved into close proximity to said key hole when the bolt is carrying the same protracted, and 10 removed therefrom when said bolt is retracted, whereby a key inserted in said key hole can not be rotated therein when the bolt carrying said ward is protracted unless the bit will pass through the slot formed 15 in said ward.

7. In combination, in a multiple key lock, a case having a key hole, inside and outside bolts in said case, a ward formed upon one 20 of said bolts having a portion extending substantially across the interior of said lock, said ward being positioned to be moved into close proximity to said key hole when the bolt carrying the same is protracted and removed therefrom when said bolt is retracted, 25 whereby a key can not be rotated in said key hole when the bolt carrying said ward is protracted unless its bit is cut to clear said ward.

8. In combination, in a mortise lock, a

plurality of dead bolts, said lock having a 30 key-hole positioned to receive a key to operate one of said bolts, a floating ward upon another bolt projecting laterally therefrom and lying substantially across the interior of said lock, said ward positioned to block 35 the rotation of a plurality of keys within said key-hole when said ward carrying bolt is moved to one position and to clear the rotation of said keys when said bolt is moved to another position. 40

9. In combination, in a mortise lock, a plurality of dead bolts, said lock having a key-hole positioned to receive keys to operate one of said bolts, a floating ward upon another bolt projecting laterally therefrom, 45 said ward positioned to be moved to a position adjacent said key-hole but to one side of the same when the bolt carrying the same is protracted and to be moved out of the path of the keys when said bolt is retracted, 50 whereby keys may be inserted within said key-hole when said ward carrying bolt is protracted but cannot be rotated therein unless they are cut to clear said ward.

In testimony whereof I have hereunto set 55 my hand on the 26 day of January, 1918.

JOHN H. SHAW.

Copies of this patent may be obtained for five cents each, by addressing the "Commissioner of Patents, Washington, D. C."

It is hereby certified that in Letters Patent No. 1,302,863, granted May 6, 1919, upon the application of John H. Shaw, of New Haven, Connecticut, for an improvement in "Locks," errors appear in the printed specification requiring correction as follows: Page 3, line 9, claim 6, strike out the word "is"; same page, line, and claim, before the word "protracted" insert the word *is*; and that the said Letters Patent should be read with these corrections therein that the same may conform to the record of the case in the Patent Office.

Signed and sealed this 3d day of June, A. D., 1919.

[SEAL.]

J. T. NEWTON,

Commissioner of Patents.
